CIRCUIT INTERRUPTER

Kurt Wulsten, Berlin-Charlottenburg, Germany,
assignor to Westinghouse Electric & Manufacturing Company, East Pittsburgh, Pa., a corporation of Pennsylvania

Application February 23, 1934, Serial No. 712,535
In Germany February 25, 1933

7 Claims. (Cl. 200—168)

My invention relates generally to moderate power circuit breakers of the type used for controlling lighting and distribution feeder circuits and relates particularly to the closures and arc extinguishing devices which are used therewith.

Circuit breakers of this type present a rather complex problem to the electrical art. Because of the fact that they are very frequently used in dwelling houses and factories, the operation of the breakers must be very reliable and very safe. Further, the breaker and its closure must present an attractive appearance to the architect or prospective purchaser and, in addition, the appearance of the closure must not be marred or otherwise altered during the operation of the breaker. As against these requirements, the cost of the device must not be excessive, since the breakers compete directly with the older arrangement of a fuse and a separate switch.

20 In an effort to reduce the cost of these breakers and to improve their external appearance, it has become general practice in the art to utilize a closure for the breaker which is formed of molded insulating material. In some forms, this closure has arcing chambers molded integral therewith, and in others it includes a supplemental arcing chamber adapted to enclose the individual arc extinguishing devices associated with each pair of moving contacts.

30 To produce an attractive external finish on the breaker closure, it is practically necessary to use insulating material which comprises an organic fibre base such as pulp and a binder similar to the phenolic condensate resins or the urea resins. This type of insulating material may be readily molded into intricate forms through the application of heat and pressure, and the resulting product has a high gloss and presents a very attractive appearance.

40 Unfortunately, however, the insulating material produced by this process is not arc resistant, and if even a moderately thin section is exposed to an electric arc on one side, the other side will blister or buckle so as to completely destroy the previous attractive appearance of that side. Thus, while the process yields a comparatively inexpensive closure which is attractive in appearance and which is comparatively inexpensive, its use is not entirely satisfactory because of the possible injury to the closure which may result during the operation of the breaker.

45 The principal object of my invention, therefore, is to provide means whereby an insulating material of the type discussed above may be used 55 for enclosing the portions of a circuit breaker

or other electrical apparatus which may be exposed to the action of an electrical arc, and I prefer to accomplish this object by molding suitable arc resistant inserts into those portions of the arc passage or chamber which may come into contact with the arc during the extinguishing operation.

5 These inserts may be formed of various arc resistant materials such as asbestos, porcelain, or the like, or they may be formed of a molded 10 insulating material which utilizes an inorganic fibre such as asbestos in combination with a binder for holding the fibres together. This last arrangement is a particularly suitable one in that it permits the securing of a bond between 15 the arc resistant and the non-arc resistant portions of the closure which will not be injured by repeated rapid heating and cooling of the arc resistant portion.

20 In the preferred embodiment of my invention, I provide a multi-pole circuit breaker which utilizes a separate arc extinguishing device of the so-called arc chute type for each of the several portions and which is provided with a unitary closure for completely closing the moving 25 parts of the breaker and the individual arc chutes. Each of the individual arc chutes is formed of molded insulating material of the non-arc resistant type, and those portions of the inner surfaces of each of the arc chutes which may 30 contact the arc during the operation of the device are provided with means of arc resistant material positioned so as to prevent injury thereto, because of the heat generated by the arc. The outer closure is provided with means for defining 35 a plurality of supplementary arc chambers, and each of these is lined at those portions which may come into contact with the heated arc products with inserts of arc resisting material for preventing damage to the surface and finish of the 40 closure proper.

45 In another embodiment of my invention, I dispense with the individual arc chutes and draw the arc within suitable arc passages or chambers formed within the closure itself. These arc passages are provided with linings of arc resistant insulating material which prevent the non-arc resistant portion of the closure from being injured by the heat of the arc. This arrangement is especially suitable for use with low voltage 50 circuit breakers wherein the magnitude of the arc to be interrupted is not excessively large.

55 By molding the arc resistant inserts integral with the closure itself, a considerable reduction of the cost of the breaker is effected, and in ad-

dition, the physical dimensions of the breaker are reduced to a minimum. This reduction is made possible by virtue of the fact that the walls of a closure made in accordance with my invention may be brought much closer to the arc without danger of injury due to the heat of the arc than has heretofore been considered possible.

An ancillary object of my invention, which will be brought out somewhat more clearly in the following description of one of the preferred embodiments of my invention, is the provision of an improved arc chute which is less expensive to manufacture than the previously known devices, which maintains its original good appearance throughout its entire life, and which is capable of functioning more satisfactorily than the previously known devices.

Referring to the drawings,

Figure 1 is a side elevational view, partially in section, of a two pole circuit breaker employing the principal features of my invention.

Fig. 2 is a front elevational view, partially in section, of the circuit breaker shown in Fig. 1.

Fig. 3 is a detail plan view of one of the arc chutes used in the circuit breaker shown in Figs. 1 and 2.

Fig. 4 is a sectional view on the line IV—IV of Fig. 3.

Fig. 5 is a side elevational view of the arc chute shown in Fig. 3.

Fig. 6 is an enlarged sectional view on the line VI—VI of Fig. 5.

Fig. 7 is a sectional view on the line VII—VII of Fig. 2.

Fig. 8 is an elevational view, partially in section, of a modified form of closure for the circuit breaker shown in Figs. 1 and 2.

Fig. 9 is a sectional view on the line IX—IX of Fig. 8, and

Fig. 10 is a sectional view on the line X—X of Fig. 8.

Referring particularly to Figs. 1 and 2, the circuit breaker comprises a base 1, preferably of molded insulating material, upon which is mounted a pair of terminals 3, a pair of stationary contact members 5, a pair of movable contact members 7, an actuating mechanism 9 for moving the movable contacts 7 to the open and to the closed circuit position, a pair of arc extinguishing devices 11, each of which is adapted to be supported upon a U-shaped pole piece 13, a pair of blow-in coils 15 for energizing each of the U-shaped pole pieces 13, a second pair of terminals 17, and a suitable means 19 for connecting each of those terminals with the lower terminal 21 of the associated blow-in coils. The actuating mechanism 9 is not an important part of my invention, and any of the arrangements which are well known to the art may be utilized. A cover 23 of molded insulating material cooperates with the base 1 so as to completely enclose all of the moving parts of the breaker. Two suitably proportioned chambers 25 are molded integral with the cover 23 for enclosing the individual arc chutes 11, and the inner surfaces of each of these chambers are provided with suitable inserts 27 of arc resistant material for preventing injury to the cover proper by virtue of the heat produced by the arc.

The electrical circuit through the breaker is comparatively direct and is the same for each of the two poles. Beginning with the upper terminal 3, the current flows successively through the stationary contact 5, the movable contact 7 and its supporting shunt 29 to the upper terminal 31 of the associated blow-in coil 15, and thence through that coil to the other terminal of the breaker 17. If desired, a suitable means may be electrically connected between the lower terminal 21 of the blow-in coil 15 and the lower terminal 17 of the breaker for causing the opening of the circuit upon the occurrence of over-load conditions.

In Figs. 2 and 7, one of the arc chutes 11 has been removed from the breaker in order to show how those chutes are supported upon the outstanding portions 33 of the pole piece 13 which project through suitable holes 35 in the base 1 of the breaker. The arc chutes 11 are formed from two substantially symmetrical half sections 37 as is shown particularly in Figs. 3, 4, and 6. Each of these sections 37 is provided with a portion 39 adapted to overlappingly engage a similar cooperating portion 39 formed integral with the other half section. This is shown particularly in Figs. 4 and 6. By this arrangement, the cooperating half sections 37, when assembled, engage each other with a substantially gas-tight joint, thereby causing all of the arc products to be vented through the vent openings 41 and 43 provided in the corners of the chutes themselves.

As shown, the arc chutes 11 are rectangular in shape, this arrangement being particularly satisfactory for use in applications where the available space is a minimum. Each of the half sections 37 is provided with a recess 45 molded integral therewith for engaging one of the opposed sides 33 of the pole pieces 13 of the blow-in magnet. These side portions 33 of the pole pieces are formed of comparatively heavy material, and when the arc chutes 11 are placed in position in the assembled breaker, the two half sections 37 are securely held together against any internal pressure that may be developed within the device during the operation of the device. No means other than the side portions of the pole pieces is needed for supporting the arc chutes on the base 1 of the breaker. Suitable inserts 47 and 48 of arc resistant material are molded into the inner walls of the arc chamber formed with in each of the arc chutes 11, and these inserts 47 serve to protect the inner surfaces of the arc chutes from the heat of the arc established therein during the circuit opening operation.

I prefer to form the arc chutes 11 of my invention by a molding operation, using an insulating material which comprises an organic fibrous base and a resinous binder. While the resulting product is not arc resistant, it presents an excellent appearance, and if, as is done in the structure shown in the drawings, inserts of an arc resistant insulating material are molded into the inner walls of the device, there is no possibility of the non-arc resistant portion of the extinguishers being injured during the arc extinguishing operation. Another advantage of this form of molded insulating material is its physical strength, which is much greater than the materials heretofore used. This permits further reduction in the size of an arc extinguisher, wherein it is used, because there is no danger of the extinguisher being injured by the large mechanical forces sometimes developed during arc extinction.

The location of the narrow slot vents 41 and 43 in the corners of the arc extinguishing device 11 of my invention is of particular value in preventing the cover 23 of the breaker from being exposed to the direct flame of the arc, since the outwardly flowing gases are caused to

follow a circuitous passage in venting into the supplemental arc chambers 25. This feature of circuitous venting, which is in part made possible by the gas-tight joint resulting from the overlapping engaging portions 39 of the arc extinguishers, in combination with the inserts 27 of arc resistant material which are positioned in the adjacent portions of the breaker closure itself, serve to prevent any possible injury to the cover by the heat of the arc.

If a cover of the type shown in Figs. 8, 9, and 10 is utilized, it may be possible to eliminate the arc chutes 11 entirely. In the arrangement shown, the arc incident to the opening of each pole is drawn within an arc chamber 51 molded integrally with the cover 50 itself. Each arc chamber 51 is substantially rectangular in outline and is positioned immediately adjacent the similar chamber for the adjacent pole. A common wall 53 is utilized for separating the two chambers 51, and in order to prevent any injury to the non-arc resisting portion of the cover, arc resistant inserts 55 are molded into those portions of each of the chambers which would in the normal operation of the device contact the arc. Thus, the objects of my invention are accomplished in a simple and inexpensive manner.

In order that the appearance of the circuit breaker may be uniform, I prefer to form both the base and the cover of the same type of molded insulating material. This material, as mentioned above, preferably comprises an organic fibrous base and a resinous binder. The arc resistant inserts may be formed of asbestos board, or of a ceramic refractory material, or, if desired, they may be formed of an insulating material which comprises an inorganic fibre base and a resinous binder therefor. This last type is one which I find particularly suitable for accomplishing the objects of my invention, because by a proper selection of the two resinous binders, it is possible to secure a bond between the arc resistant and the non-arc resistant portions of the closure, which is not in any way injured by the repeated rapid heating and cooling incident to the interruption of any arc.

From the above, it will be seen that I have provided means whereby a non-arc resistant insulating material, such as the moldable compound of 50 pounds of an organic fibre and a resinous binder, may be used in the formation of a closure for electrical apparatus without having to consider whether or not an arc may be drawn within the closure during the operation of the device. By virtue of my invention, I am able to considerably decrease the physical dimensions and at the same time eliminate any possible danger of injury to the non-arc resistant portion of the closure because of the heat of the arc. Moreover, the features of my invention permit the securing of an increased margin of safety to apparatus wherein they are incorporated, because of the fact that the insulating material which is used for the closure may be selected not on the basis of its arc resisting qualities but on the basis of its mechanical strength and good appearance.

In addition to the above, I have disclosed the features of an improved closure for a multi-pole circuit interrupter or like device which permits the utilization of a non-arc resistant material for the outer surface thereof, in order that a desirable appearance may be achieved, and which at the same time is provided with arc passages molded integral therewith, this improved closure

being provided with means for preventing injury to the appearance of the non-arc resisting portion thereof by the heat of the arcs which are established in the arc passages during the operation of the device.

I have also shown an improved form of arc chute which is readily assemblable to form an arc-extinguishing device wherein the outward flow of the arc products is carefully controlled, and which may safely be formed of non-arc resisting insulating material without any danger of that material being injured by virtue of the heat of the arc.

In accordance with the patent statutes, I have disclosed the details of a preferred embodiment of my invention. Most of these details are, however, merely illustrative, and it is my desire that the accompanying claims shall be accorded the broadest reasonable construction and shall be limited only by what is explicitly stated therein and by the prior art.

I claim as my invention:

1. In electrical apparatus, means for establishing an arc, and means for extinguishing said arc comprising an arc chamber which is substantially rectangular in outline and within which said arc is established by said arc establishing means, the walls of said arc chamber being formed by the assembling of two substantially symmetrical half sections, each of said half sections having a portion adapted to overlappingly engage a similar portion formed integral with the other section so as to form a substantially gas-tight joint, and including vent means comprising narrow slots disposed adjacent the corners thereof so as to be spaced some distance from said joint.

2. In a device for extinguishing electrical arcs, means of insulating material for defining an arcing chamber which is open on not more than one of its sides, said means including two substantially symmetrical half sections of molded insulating material, each of which has a portion adapted to overlappingly engage the cooperating section so as to form a substantially gas tight joint and has means of arc-resistant insulating material molded into the walls thereof for protecting at least a portion of the inner surface of each of said sections from the heat of the arc, and means for defining vents in said arcing chamber, said vents being spaced some distance from said gas tight joints.

3. In a device for extinguishing electrical arcs, means of insulating material for defining an arcing chamber which is substantially rectangular in outline and which is closed on its top, bottom, and at least three sides, said means including two substantially symmetrical half sections of molded insulating material, each of which has a portion adapted to overlappingly engage a similar portion formed integral with the other section so as to form a substantially gas tight joint and has means of arc-resistant insulating material molded into the walls thereof for protecting at least a portion of the inner surface of each of said sections from the heat of the arc, and means for defining vent slots in said arcing chamber, said vent slots being disposed adjacent the corners of said chamber.

4. In a device for extinguishing electrical arcs, means of insulating material for defining an arcing chamber which is open on not more than one of its sides, said means including two substantially symmetrical half sections which are molded from an insulating material comprising a fibrous base and a resinous binder, each of said sections

- having a portion adapted to overlappingly engage a similar portion formed integral with the other section so as to form a substantially gas-tight joint and having means of arc resistant insulating material molded into the walls thereof for protecting at least a portion of the inner surface of each of said sections from the heat of the arc, and means for defining vents in said arcing chamber, said vents being spaced some distance from said gas tight joints.
5. In a device for extinguishing electrical arcs, means of insulating material for defining an arcing chamber which is open on not more than one of its sides, said means including two substantially symmetrical half sections formed of molded insulating material, each of said sections having a portion which is adapted to overlappingly engage a similar portion formed integral with the other section so as to form a substantially gas-tight joint, and means for defining vents in said arcing chamber, said vents being spaced some distance from said gas-tight joints.
10. In a device for extinguishing electrical arcs, means of insulating material for defining the walls of an arcing chamber which is normally open on not more than one of its sides, said means including two substantially symmetrical half sections of molded insulating material, each of which has a portion adapted to overlappingly engage a similar portion formed integral with the other section so as to form a substantially gas-tight joint, and means for defining vent slots in said arcing chamber, said vent slots being spaced some distance from said gas-tight joints.
15. In a device for extinguishing electrical arcs, means of insulating material comprising a fibrous base and a resinous binder, each of said sections having a portion adapted to overlappingly engage a similar portion formed integral with the other section so as to form a substantially gas-tight joint and having means of an insulating material which comprises an inorganic fibre base and a binder molded into at least a portion of the walls thereof, in order to provide arc resistant inserts for protecting the inner surfaces of said arc chamber from the heat of the arc, the said resinous binder and the binder used for the said inserts being capable of forming a bond between said walls and said inserts which will withstand

repeated heating and rapid cooling of said inserts, and means for defining vents in said arcing chamber, said vents being spaced some distance from said gas tight joints.

6. In a device for extinguishing electrical arcs, means for defining the walls of an arcing chamber, including two substantially symmetrical half sections formed of molded insulating material, each of said sections having a portion which is adapted to overlappingly engage a similar portion formed integral with the other section so as to form a substantially gas-tight joint, and means for defining vents in said arcing chamber, said vents being spaced some distance from said gas-tight joints.

7. In a device for extinguishing electrical arcs, means of insulating material for defining the walls of an arcing chamber which is normally open on not more than one of its sides, said means including two substantially symmetrical half sections of molded insulating material, each of which has a portion adapted to overlappingly engage a similar portion formed integral with the other section so as to form a substantially gas-tight joint, and means for defining vent slots in said arcing chamber, said vent slots being spaced some distance from said gas-tight joints.

KURT WULSTEN.
